(57) CLAIM

The ornamental design for a hanger counter, as shown and described.

DESCRIPTION

FIG. 1 is a perspective view of a hanger counter showing the new design installed on a hanger.

FIG. 2 is a perspective view of a hanger counter showing the new design not installed on a hanger.

FIG. 3 is a top view of a hanger counter showing the new design.

FIG. 4 is a bottom view of a hanger counter showing the new design.

FIG. 5 is a first side view of a hanger counter showing the new design.

FIG. 6 is a second side view of a hanger counter showing the new design.

FIG. 7 is a front view of a hanger counter showing the new design; and,

FIG. 8 is a rear view of a hanger counter showing the new design.

The broken lines are for illustration only and form no part of the claimed design.
